I claim the ornamental design for a cap, as shown and described.

DESCRIPTION

FIG. 1 is a front perspective view of a cap shown in a closed position;

FIG. 2 is a right side elevational view thereof;

FIG. 3 is a front side elevational view thereof;

FIG. 4 is a top view thereof;

FIG. 5 is a front perspective view of the cap of FIG. 1 shown in an open position;

FIG. 6 is a back perspective view thereof;

FIG. 7 is a right side elevational view thereof; and,

FIG. 8 is a top view thereof.

The broken lines depict portions of the cap that form no part of the claimed design.

1 Claim, 7 Drawing Sheets(56)
